UNITED STATES PATENT OFFICE.

CHARLES N. MANGOLD, OF PITTSBURGH, PENNSYLVANIA.

PIANO.

1,417,191.

Specification of Letters Patent. Patented May 23, 1922.

Application filed June 30, 1921. Serial No. 481,447.

To all whom it may concern:

Be it known that I, CHARLES N. MANGOLD, a citizen of the United States, and a resident of Pittsburgh, in the county of Allegheny and State of Pennsylvania, have invented a new and useful Improvement in Pianos, of which the following is a specification.

The invention relates to transpositional pianos wherein the keyboard is capable of movements relative to the action of the piano both for the purpose of playing a piece in the key in which it is written and have it transposed to a different key, and for the purpose of raising or lowering the pitch of the piano without the necessity of tuning it.

While the invention is applicable to newly constructed pianos, it is particularly adaptable to the reconstruction of old pianos, and the object thereof is to provide a simple and effective way of building or reconstructing a piano to the end that the keyboard may be readily shifted for the purposes stated.

Ordinarily, pianos are tuned for what is known as standard pitch. Occasionally, it is desired to have a piano in a home tuned up to concert pitch for a special occasion. This is difficult to do at any time, and is practically incapable of accomplishment if the piano is old because of the serious liability of breaking a large number of strings. According to this invention, the pitch of the piano may be easily changed at will.

The invention is illustrated in the accompanying sheets of drawings of which Fig. 1 is a combined plan and sectional view of a piano, the view being taken just above the keyboard on the plane indicated by the line I—I of Fig. 2; and Figs. 2, 3, 4, and 5, are sectional views taken, respectively, on the lines II—II, III—III, IV—IV and V—V, Fig. 1.

In the practice of the invention, the keyboard and action may be of standard or any desired form of construction, except that the keyboard is mounted for lateral movements. In the illustrative embodiment of the invention, the keyboard frame comprises longitudinal members 1 and 2, end cross-members 3, intermediate cross-members 4, and an intermediate longitudinal member 5 provided on its upper face with the usual pins 6 on which the keys 7 are pivoted. A portion of the intermediate bar 5 projects downwardly through a slot 26 in a board 27 upon which the keyboard frame

is slidably mounted. To hold the keyboard in any one of its several positions, bar 5 may be provided with suitable openings through which a pin 8 may extend into openings provided in a board 9 extending downwardly from the supporting board 27. By removing pin 8, the keyboard may be shifted from one to another of its positions and the pin thereafter inserted to hold the keyboard in place. To prevent vibration of the movable keyboard frame, suitable spring clips 10 may be mounted upon board 27 and constructed to extend over the tops of cross-members 3 and 4, the upper faces of which may be provided with padding such as strips of felt 11.

The action of the piano is shown as being of standard upright piano construction supported by an upright frame 12. Just below the offsets 13 of the action rods 14 there is arranged a horizontal bar 15 which holds the lower end of the action rods just in contact with the striking pins 16 mounted on the rear ends of the keys. This fixed supporting bar 15 holds the action rods against falling or moving downwardly when the keyboard is shifted laterally, and it in no way interferes with the proper functioning of the action at all times. Preferably, the upper face of supporting bar 15 is provided with a pad such as a strip of felt 17.

As usually constructed, the upright action-supporting frames 12 of a piano are supported intermediate their ends by brackets 90 so located that adjacent keys diverge from each other to clear the brackets. In Fig. 1 keys 7^a and 7^b show the manner in which keys so diverge. In the practice of this invention, the intermediate brackets found in standard constructions for supporting action frame 1, are removed and replaced by brackets 18 secured to a member 19 of the piano casing, and extend upwardly back of the keyboard in the manner illustrated particularly in Fig. 5.

So that there will not be a silent key at each point of diverging pairs of keys when the keyboard is shifted to one side or the other of its standard pitch position, the diverging pairs of keys are provided with lateral extending blocks having action-striking pins. As seen in Fig. 1, key 7^a has attached to its side a block 20 provided with a striking pin 21, and key 7^b has attached to its side a block 22 provided with a striking pin 23. The arrangement of these blocks

and the pins is such that, for example, when the keyboard is moved to the right of its normal standard pitch position, the action rod that was previously struck by the pin on key 7^b is struck by pin 21 of block 20 attached to key 7^a, and that when the keyboard is moved to the left, the action rod that was struck by the pin on key 7^a is struck by pin 23 of block 22 attached to key 7^b.
10 Thus, in all positions of the keyboard, all keys are brought into action.

The reconstruction of an upright piano according to this invention, may be effected with a minimum amount of labor without in 15 any way prejudicially affecting the piano. To reconstruct the piano, it is only necessary to modify the construction of the keyboard frame so that it may be moved laterally in the manner explained, replace the 20 ordinary intermediate action supporting the brackets by the rear brackets 18, and provide the action supporting frame with a fixed bar 15 to hold the action rods against falling or moving downwardly when the 25 keyboard is shifted. Manifestly new pianos may be readily built to include the same feature of construction. According to the provisions of the patent statutes, I have described the principle and operation of my 30 invention together with the construction which I now consider to represent the best embodiment thereof. However, I desire to have it understood that, within the scope of the appended claims, the invention may be 35 practiced by other forms of construction than that specifically shown and described.

I claim:

1. In a transposing piano, a laterally

movable keyboard, a fixed action including action rods, and a fixed bar forming a vertical support for the action rods and thereby holding them upwardly in positions permitting free lateral movement of the keyboard.

2. In a transposing piano, a laterally movable keyboard, a fixed action having upright action rods provided with horizontal offsets, and a fixed bar forming a vertical support for the action rods at said offsets and thereby holding the action rods upwardly in positions permitting free lateral movement of the keyboard.

3. In a transposing upright piano, a laterally movable keyboard provided with keys the rear ends of some of which diverge from each other, a fixed action including upright action rods, a frame supporting said rods, upwardly extending brackets back of the keyboard, the rear ends of adjacent pairs of diverging keys being provided with laterally extending blocks having action-striking pins arranged to bring all keys into action in all positions of the keyboard.

4. In a transposing piano, a laterally movable keyboard including a frame having longitudinal and transverse members, yielding means for holding said frame down, a fixed action including upright action rods, and a fixed bar forming a vertical support for each of the action rods and thereby holding them upwardly in positions permitting free lateral movement of the keyboard.

In testimony whereof, I sign my name,
CHARLES N. MANGOLD.

Witness:

EDWIN O. JOHNS.
